UNITED STATES PATENT OFFICE.

WALTER G. CLARK, OF NEW YORK, N. Y., ASSIGNOR TO PARKER-CLARK ELECTRIC COMPANY,
OF NEW YORK, N. Y., A CORPORATION OF NEW JERSEY.

ELECTRICALLY-HEATED TOOL.

No. 858,955.

Specification of Letters Patent.

Patented July 2, 1907.

Application filed October 6, 1906. Serial No. 337,817.

To all whom it may concern:

Be it known that I, WALTER G. CLARK, of the city, county, and State of New York, have invented a new and Improved Electrically-Heated Tool, of which the following is a full, clear, and exact description.

My invention relates to improvements in electrically heated tools and especially to improvements in a tool which is intended to carry a pen, electric contact or analogous metallic instrument in a convenient way so 10 that the same may be quickly and highly heated and can be easily placed in or removed from the tool.

My invention is especially useful in carrying into effect in certain special ways the process of producing coatings of metallic iridium set forth in Letters Patent 15 of the United States, No. 805,316, dated November 21, 1905, though the tool can be used for other purposes.

In coating pen points and electric contacts with iridium it is difficult by ordinary means to apply the iridium in the right quantity and at the precise part 20 where it is needed. I find in practice that the metal as it is produced, has a tendency to work away slightly from the source of heat. Consequently I have found that by supporting a pen in a heated holder so that the pen will become quickly heated but with the 25 point protruding and then bringing the point into a composition of iridium ammonium chlorid and ammonium chlorid, as set forth in the patent above referred to, the metal is quickly reduced and adheres to the pen point.

30 The object of my invention is to produce a convenient holder for carrying pens, contact rivets and analogous things which will heat them rapidly and will permit of their being easily placed in position or removed.

With these ends in view my invention consists of an 35 electrically heated instrument, the construction of which will be hereinafter described and the novel features claimed.

Reference is to be had to the accompanying drawings forming a part of this specification, in which similar figures of reference indicate corresponding parts in 40 all the views.

Figure 1 is a longitudinal section of the tool embodying my invention; Fig. 2 is a longitudinal section of the tool head the section being at right angles to that 45 shown in Fig. 1; and Fig. 3 is a cross section through the tool head.

The tool forms really a double heater with concentrically arranged heating parts so that when a pen is heated for instance, the heat will be or may be applied on both sides simultaneously, so that quick heating results. I have an internal heater 10 in the 50 form of a tube, although the body portion of it may be

in rod form if preferred, and I preferably make the heating portion 10 as well as the other heating parts 12 and 13 to be presently referred to, of quartz as this material is a fairly good conductor of heat, but a non-conductor of electricity. In this way I can bring the quartz into contact with the article to be heated without the necessity of interposing a non-conductor through which it may be difficult to drive the necessary 60 heat. Thus I gain in efficiency over the ordinary heater.

The tube or core 10 is heated by a heater 11 which is coiled around it and is shown conventionally as a resistance wire, but it may conveniently be a resistance coating on the outer wall of the tube and it will be seen that the same heater will heat the tube or core 65 10 and the tube 12 which is concentric with the tube 10 and lies against the heater 11. The tube 12 can have its lower or outer end turned inward as shown to 70 prevent any displacement of the heating parts.

Surrounding the tube 12 and concentric therewith is another heating tube 13 which like the others, is preferably of quartz, and this is spaced apart from the tube 12 sufficiently to permit a pen, as 18, to be placed 75 in between the parts 12 and 13, as in an ordinary pen holder, and conveniently held. The tube 13 is heated by a heater 14 on its exterior wall and the tube can be turned up at the ends to assist in holding the heater or to prevent it from coming in contact with any extraneous substance, if desired. Surrounding the heater 14 is suitable insulation 15 and a casing 16 incloses the whole heater head. In the drawings I have shown in Fig. 2, the parts 10, 12, 13 and 15, in open section instead of in black, in order that the leading lines can 80 appear.

The head which carries the parts already described carries also the terminals 19 which suitably connect with the heaters 11 and 14 and these can be united in a cable 20 which extends up through a handle 21. 90

If pens are to be heated the operator takes, with a pair of nippers, the pen 18 and thrusts it into the socket between the parts 12 and 13 and the pen is instantly heated, and then by embedding its point in the salts of iridium ammonium chlorid and ammonium chlorid, the iridium metal is reduced and adheres to the pen point. If a contact as 17 is to be treated the contact is inserted in the end of the tube 10 and the projecting part can be brought into contact with the salts which are to be reduced. 95

It is obvious that the heating tool can be given any desired form, that the connections between the parts can be made in any usual or suitable manner and that the sockets formed between the parts 12 and 13, 100

and in the end of the tube 10 can be made of varying shapes to suit whatever articles are to be treated, without affecting the principle of the invention.

Having thus fully described my invention, I claim 5 as new and desire to secure by Letters Patent,—

1. A handled tool having a socket formed between concentric walls, which are spaced apart to produce the socket, and with an electric heater in contact with each wall.
- 10 2. A handled tool having a curved socket formed between concentric walls which are non-conductors of electricity, and which are spaced apart to produce the socket, and electrical means for heating the said walls.
- 15 3. A handled tool having a central implement-receiving socket, and a second socket with concentric walls, the walls of both said sockets being electrically heated.
4. A handled tool having a plurality of holding sockets

each socket having walls which are non-conductors of electricity but conductors of heat, and electric heaters in contact with the said walls.

20

5. A heating tool comprising a central core which is a non-conductor of electricity, and has a socket in the end, an electrically non-conducting tube concentric with the said core, an electric heater between and in contact with the said core and tube, and a second electrically heated tube 25 being concentric with the first tube and spaced therefrom to form a socket between the two tubes.

6. A handled tool having sockets with walls which are conductors of heat but not of electricity, and electric 30 heating means in direct contact with the said socket walls.

WALTER G. CLARK.
